INVENTOR

BY *Victor J. Evans*

WITNESS: *John Donoran*

ATTORNEY

UNITED STATES PATENT OFFICE.

CHARLES CARROLL CAMBRIDGE, OF SAVANNAH, GEORGIA.

FUEL TANK.

Application filed August 9, 1926. Serial No. 128,207.

This invention relates to new and useful improvements in filling nozzles for tanks and more particularly to a device of this character which is used on the gasoline supply tanks of motor vehicles or the like and the main object of the invention is the provision of a new and improved filling nozzle to prevent removal of the contents of the tank by syphoning or in a similar manner.

Another object of my invention is a provision of a filling nozzle for gasoline storage tanks whereby the tank may be readily filled through the nozzle but it will be impossible to siphon out the contents of the tank through the said nozzle thus preventing pilfering of the contents of the tank.

With the above and other objects in view the invention consists in the novel features of construction, the combination and arrangement of parts to be hereinafter more fully set forth, pointed out in the claim and illustrated in the accompanying drawings, in which:—

Figure 1 is a side elevation of a gasoline storage tank illustrating the application of my invention, parts thereof being broken away and illustrated in cross section.

Figure 2 is a view similar to Figure 1 showing the modified form of my invention, and

Figure 3 is a detail sectional view on the line 3—3 of Figure 1.

Referring now, more particularly to the drawings, the numeral 1 illustrates the storage tank which may be used for the storage of gasoline on motor vehicles or any other purpose desired. The tank 1 is provided adjacent one end thereof with a filling opening around which is an upstanding interiorly threaded flange 2 and threaded into this flange is a portion of my improved nozzle.

The nozzle includes a substantially straight portion 3 which is exteriorly threaded part of its length to cooperate with the threads upon the interior of the flange 2. The lower end of the nozzle projects into the tank below the upper side thereof as illustrated in Figure 1 and is provided with a perforated plug 4 which will permit gasoline or other liquid to enter the tank 1.

The nozzle includes a goose-neck 5, one end of which connects with the straight portion 3 while the other end thereof is extended laterally as at 6 and thence upwardly as at 7

and the extreme outer end of the nozzle is 55 threaded to receive thereon the closure cap 8. From this it will be apparent that gasoline may be ejected into the tank 1 by removing the cap 8 and placing the nozzle of a hose pipe within the upwardly extending 60 portion 7 and the force of discharge of the liquid from the nozzle will cause the fluid to travel upwardly through the goose-neck portion 5 and through the nozzle, into the tank. As shown in Figure 1 the straight 65 portion is secured in position by means of a lock nut 9 threaded onto the straight portion and bearing against the flange 2.

It will be apparent that this form of nozzle or filling pipe may be placed in different 70 makes of gasoline storage tanks which are in use upon different types of motor vehicles, at the present time. However I have illustrated in Figure 2 a slightly modified form 75 of my invention or filling pipe of nozzle 10, one end of which projects into the flange 3, surrounding the filling opening, while the other end projects into the tank with its inner end provided with a perforated plug 11 80 to permit the fluid to enter the tank. In this form of the invention the flange 2' is provided with the usual cap 8' for closing the outer end of the filling pipe 10.

It will be noted that the device acts as an 85 anti-splash device and by positioning the nozzle upon the interior of the tank as shown in Figure 2 it is entirely out of the way and no damage will be incurred of having the same disconnected from the neck 2'.

It will be apparent from the foregoing 90 that I have provided a simple and inexpensive device of the character described which can be manufactured and placed upon the market at a very low cost and which will 95 prevent syphoning of the contents of the gasoline in a storage or similar tank and can be attached to storage tanks of different types.

While I have shown and described the preferred embodiment of my invention it will 100 be understood that various changes and alterations may be carried out for putting my invention into practice without departing from the spirit of the invention or the scope 105 of the appended claim.

Having described the invention, what I claim is:—

In an anti-theft device for gasoline tanks, the combination with a tank having a flanged inlet opening, of a goose neck having a straight portion arranged in said opening, a curved portion formed with said straight portion, a perforated plug secured in the free end of said straight portion which is disposed adjacent the top of said tank and being adapted to prevent a hose from being arranged in the bottom of said tank to siphon the contents thereof, and a cap for said goose neck. 10

In testimony whereof I affix my signature.
CHARLES CARROLL CAMBRIDGE.
